A. C. Barstow, Providence R. I. Letters
Patent No 227 dated July 10. 1849

The Schedule referred to in these Letters Patent and making part of the same.

To all Persons to whom these Presents shall come.

Be it known

that I A. C. Barstow of Providence in the County of Providence, have invented or produced a new and original design for the bottom and front of a cooking stove, known by the name of the "Bay State coal cook stove," and that the following description taken in connection with the accompanying drawings, forms a full and exact specification of the same.

The figures of the accompanying plates of drawings, represent my new design. In Plate 1, Fig. 1 is a top view of the bottom plate, and Fig. 2 is an elevation of the front plate of said stove, shewing the ornamental carvings on the same. In Plate 2, Fig. 3 is a vertical section taken in the plane of the line A.B. Figs. 1 & 2 - and Fig. 4 is a horizontal section taken in the plane of the line C.D. Fig. 2 - said last two figures shewing the sectional contour of the castings.

That portion of the bottom plate which supports the main body of the stove, is nearly rectangular, as shown at a a a a in Fig. 1 Plate 1, and has around the exterior of the three sides, the narrow curved moulding b b b b shown in said figure, and just within this moulding and on a concave face, extending round the same three sides referred to, are formed the pointed ribs c c c c - the side plates being set against the vertical flange d d d d cast for the purpose.

The hearth plate e e e e - is cast with and makes a portion of this bottom plate and the sliding

ash-plate $g'g'g'g$ is so arranged, as that its ornamented edge may fit into and make a portion of that about said hearth, as shown in Fig. 1. The said edge of said hearth and ash-plate, has an ogee moulding all around it, as shown in Fig. 1 Plate 1, at ff , which moulding is ornamented with a serpentine string of water leaves $ffff$ with sunken mid ribs as shown in said Fig. 1.

The inner side of the ash plate $g'g'g'g$ is fitted with an upright ledge, $h'h'h$ Figs. 1 & 2, Plate 1, which is curved oppositely with the front of the stove, and has cast on its exterior face, the wedge shaped ribs shown in said figures at $h'h'h$, so as to conform to similar ribs formed on the bottom of the front plate, shown at iii - on each side of said ledge.

The front plate Fig. 4 Plate 1, is curved as shown in horizontal section in Fig 2 Plate 2, and has a narrow moulding $kk'kk$ around the two sides and top.

There are an upper and lower set of enriched double doors hung on this front plate, and between them an ornamental tablet, the upper doors being straight, and the lower ones with the tablet, being curved to conform to the swell of the main front-plate. All around these several doors and the said tablet is a triple moulding shown at $lll-l' l l$ &c. on the upper doors, at $m m m m$ &c. on the lower ones, and at $n n n n$ &c. round the tablet. At the centre of each of the doors, is a plain circular panel 0000 &c. and a plain panel p in the centre of the tablet, of the shape shown in Fig. 2. Plate 1; from each of these panels, radiate the triangular ribs $qq'qq'q$ &c. shown in said Fig. 2 Plate 1.

On each side of each set of doors, and

3

Ms. 227

of the tablet above referred to, is a lozenge or diamond, rrr, rrr, ornamented with a plain circular panel, radial ribs, and a surrounding moulding, as shown in the aforesaid Fig. 2 - while between the sides of the tablet and its adjacent ornamented diamonds, are placed or cut, the elongated skeleton diamonds sssss, having plain rings tt-tt, at the ends of each of them.

Having ^{thus} described my new design, I shall state my claim as follows -

What I claim as my invention or production, and desire to have secured to me by Letters Patent, is the combination of Mouldings, panels, ornamental carvings or configurations, herein above described and represented in the drawings for the several doors, and other parts of the front and bottom plates, of the "Bay State coal Cook Stove."

Providence May 12 A. D. 1849.
